HEADBOARD FOR A BED

Max S. Dresher, Chicago, Ill.

Application November 24, 1958, Serial No. 53,492

Term of patent 7 years

(Cl. D5—4)

The dominant features of my design reside in the portions shown by means of full lines in the drawing.

I claim:

The ornamental design for a headboard for a bed, substantially as shown and described.
